CATHODE RAY TUBE

Frederick Hermes Nicoll, Ickenham, England, assignor to Electric & Musical Industries Limited, Hayes, Middlesex, England, a company of Great Britain

Application November 18, 1938, Serial No. 241,092
In Great Britain November 19, 1937

3 Claims. (Cl. 250—141)

This invention relates to cathode ray tubes of the kind that are used for the generation of electrical signals for television transmission, for the reproduction of such signals and for use in cathode ray oscilloscopes and for other purposes.

In cathode ray tubes of this kind a beam of electrons is generated in a cathode ray gun comprising a cathode and several additional electrodes which are employed for a variety of purposes, such as for screening the cathode, for focussing the electron beam, for modulating the electron beam and for other purposes depending upon the type of cathode ray tube to which the gun is applied. In all cases it is necessary to mount the gun co-axially with respect to the neck of the cathode ray tube and such operation entails considerable difficulty if the gun is to be accurately centered. The neck of the cathode ray tube in which the gun is mounted is usually formed of glass tubing which is attached to the other portion of the envelope and it is found difficult to obtain glass tubing of sufficiently accurate internal dimensions to enable the gun to be aligned merely by inserting the gun in the neck of the tube and allowing it to make contact with the internal diameter of the tubing. In cases where the envelope of the tube is blown or made integrally with the neck of the tube the same difficulty arises. Various devices have been proposed, such as the provision of spring fingers and the like, for accurately centering the gun in the neck of the tube, but all these proposals depend fundamentally on the accuracy of the internal diameter of the neck.

The object of the present invention is to provide an improved cathode ray tube whereby the gun can be more easily and accurately centered in the neck of the tube. According to one feature of the present invention there is provided a glass envelope for a cathode ray tube the neck of which is provided with internal depressions such that in any given plane perpendicular to the axis of the neck the distances of the internal depressions from the center of the neck are substantially constant for accurately and rigidly aligning the cathode ray gun structure in said neck.

In order that the present invention may be clearly understood and readily carried into effect it will now be described with reference to the accompanying drawing which illustrates embodiments of the present invention by way of example and in which:

Figure 1 illustrates a longitudinal section through a portion of a cathode ray tube,

Figure 2 illustrates an end-view taken in the plane 2—2 of Figure 1.

Figure 3 illustrates a longitudinal section of a portion of the neck of a cathode ray tube.

Figures 4 and 5 illustrate plans of spacing elements, used for engaging the gun structure with the depressions in the tube.

Figure 6 illustrates a longitudinal section through a modified form of glass envelope for a cathode ray tube.

In Figure 1 the neck of a cathode ray tube 1 has angularly spaced depressions 3 formed thereon, these depressions being formed in two sets which are spaced longitudinally apart with respect to each other. Inserted in the neck of the tube is the cathode ray gun structure having insulating or spacing elements 4, which may be mica discs, two of which spacing elements engage with the depressions 3 in the neck.

In the embodiment illustrated in Figures 1 and 2, the insulating element 4 in the plane 2—2 which engages with the depressions 3, has depressions 5 formed therein which are of such dimensions so that the shoulder of the depression 5 fits fairly closely about the shoulder of the depressions 3 in the neck so as to tend to prevent rotational movement of the gun structure in the tube. The depressions 3 in the tube, formed according to one feature of the present invention, have a substantially uniform internal diameter so that the insulating elements 4 may be readily fashioned to engage accurately therewith. In the embodiment shown, the depressions are spaced angularly apart at angles of 120 degrees with each other.

The insulating elements 4 of the gun structure are provided with holes 6 therein through which are riveted short supporting elements for the supporting rods 7 which run substantially the length of the gun. The cathode of the gun, which may be an indirectly heated element, has a screening electrode 8 in the form of a longitudinal cylinder, the cylindrical electrode 8 being provided with a shaped metal disc 9 in the region of the plane 2—2, the insulating element 4 being riveted to this shaped metal disc 9 by rivets 10.

The internal diameter between the depressions 3 being substantially uniform provides means for accurately positioning the gun with respect to the tube by the engagement of the insulating elements and the depressions, the insulating elements being readily fashioned to engage with said depressions. The engagement between the insulating elements and the depressions may be in the nature of a push fit, or

notches in the insulating elements may engage the depressions as shown in Figure 2, or projections on said insulating elements as shown on Figure 5 may engage the depressions, or projecting lugs on said insulating elements may engage further suitably shaped depressions formed in said depressions as shown in Figures 3 and 4, these figures being hereinafter more fully referred to. The engagement between one or more 10 of said insulating elements and the depressions in the tube may be such as to tend to prevent rotational movement of the gun structure in the tube, while the engagement of one or more other of said insulating elements with said depressions may be such as to tend to prevent longitudinal movement of the gun structure with respect to the tube.

The gun structure is thus firmly supported in the neck and the use of the usual band around 20 the pinch or reentrant neck portion of the tube for supporting the gun structure may be dispensed with. The pinch of the envelope through which the conducting leads to the various electrodes of the gun extend may be relieved of one 25 of its usual functions of supporting the gun, the support for the latter being effected due to the engagement of the insulating elements with the said depressions and with such a construction, the conducting leads may be brought out at the 30 periphery of the neck of the tube, as at 16, Figure 1, and a "ring pinch" may be used for sealing off the end of the neck of the tube. The leads which are connected to the pinch may serve to prevent relative rotational movement between the 35 gun and the neck of the tube.

The glass tubing employed in the construction of the cathode ray tube is preferably mould-blown and the depressions may be formed in the tubing after the tubing is formed and prior to 40 the connection of the tubing of the other portion of the envelope of the cathode ray tube. The depressions may be formed by locally heating the tubing in the region where the depressions are to be formed so that the tubing contacts with a cylindrical former preferably of metal which has been inserted into the neck, the depressions being formed by the application of pressing tools to the outer surface of the tubing. Since the former is cylindrical, the inner surfaces of the 45 depressions are cylindrical and co-axial with the tubular neck, and elemental areas of the inner surfaces of the depressions are equi-distant from the longitudinal axis of the tubing. After the depressions are formed the tubing is annealed.

50 In Figure 3 is illustrated a portion of a neck of a cathode ray tube which is provided with a depression 3 therein, which depression is provided with a further depression 11 therein. The depression 11 is preferably of substantially V-shape. By providing an insulating or spacing element of the gun structure with suitably shaped projections 13 as shown in Figure 4, these latter may be made to engage with the further depressions 11, and such engagement will tend to 55 prevent longitudinal movement of the gun structure with respect to the tube.

A construction of insulating or spacing element is illustrated in Figure 4 wherein the insulating 60 element has generally an external diameter to correspond with the internal diameter of the tube between the depressions but is provided with projecting lugs 13, which projecting lugs are arranged to engage with additional depressions 70 such as 11, Figure 3. The outer edges of the lugs

13 are preferably arranged accurately to engage the apices of the further depressions 11.

A modified form of insulating or spacing element is illustrated in Figure 5. The insulating element here illustrated is cam-shaped, having 5 a maximum diameter at certain points thereof which gradually decreases to a minimum, and at these points increases to a maximum again, a series of projecting edges 12 thus being formed. The mica disc illustrated in Figure 5 is formed 10 with three projecting edges 12 spaced so as to be substantially equi-distant around the periphery, the minimum external diameter of the disc so formed being too small to contact with the depressions in the neck of the tube, while the maximum external diameter of the disc so formed is greater than the internal diameter of the tube with the depressions therein. A cathode ray gun structure embodying such a spacing element may thus be readily inserted into the tube and rotated until the spacing element contacts firmly 15 with the depressions formed in the tube. The use of such a spacing element is advantageous when the tube is often dismantled and reassembled as different parts of the periphery of the mica disc, 20 which tend to become damaged by such treatment, may be employed for ensuring rigid mounting of the gun structure. It has been found that a suitable length for a projecting edge such as 25 12 is 0.01 inch used with a tube having an internal diameter of about 1.5 inches.

In the modified form of glass envelope for a cathode ray tube illustrated in Figure 6, the neck portion 1a is of a substantially cylindrical shape and the depressions 3a formed in the neck portion are in the form of truncated cones, the method of forming the depressions according to one feature of the present invention ensuring that in a given plane perpendicular to the axis of the neck the distances of the internal depressions from the centre of the neck are substantially constant. The depressions 3a may be portions of the same cone or may be different truncated cones. Further, the neck portion 1a need not be substantially cylindrical, but may be substantially conical, and have conical depressions formed therein where the depressions 3a are formed. The former employed in the construction of such a glass envelope for a cathode ray tube may be in the form of a cone, or may be 40 conical with suitable projections thereon, or may be in the form of a cylinder having projections thereon in the form of truncated cones. The insulating or spacing elements employed with such a modified form of glass envelope may be suitably dimensioned to fit into the projections 3a, 45 while the gun structure used may be of the usual form.

Whilst it has been found preferable to provide longitudinally extended depressions, it will be understood that, if desired, the depressions may be of annular form, that is to say, they may extend around the circumference of the tubing, in which case two or more of said annular depressions will be provided, the number of depressions 55 preferably corresponding to the number of mica discs employed in the gun.

Tubes made according to the present invention are found to have internal diameters which generally conform with each other to an accuracy 60 of one to two thousandths of an inch in a tube having an internal diameter of the order of one and a half inches, so that it is seen that the present invention provides tubes of extremely accurate internal dimensions and in which, therefore, 70

the gun structure may be accurately and rigidly aligned.

I claim:

- 5 1. An envelope for a cathode ray tube having a tubular section, a plurality of narrow depressions running lengthwise of a portion of said tubular section, the inner surfaces of said depressions being cylindrical and substantially co-axial with said tubular section and the distances between the inner surfaces of said depressions and the longitudinal axis of said tubular section being substantially equal over the length of said depressions.
- 10 2. In combination, a cathode ray tube having an envelope one section of which is tubular, three equally spaced depressions around the tubular section, said depressions running lengthwise of a portion of said tubular section, the inner surfaces of said depressions being concentric with said section which is tubular and the distances between the inner surfaces of said three equally spaced depressions and the longitudinal axis of said tubular section being substantially equal over

the length of the depressions, a plurality of resilient electrode supports supported transversely of said longitudinal axis solely by said depressions at a plurality of separated points along the length of said depressions and a mount structure supported axially of said tubular section by said electrode supports and by said depressions.

- 15 3. In combination, a cathode ray tube having an envelope a portion of which is tubular, a plurality of depressions in said tubular portion equally spaced about said tubular portion, a second plurality of depressions equally spaced about and in said tubular portion but displaced lengthwise along said tubular portion from the first-mentioned depressions, an electron gun structure within the tubular portion of said envelope and a plurality of spacers on said gun structure, at least one of which is in contact with said first-mentioned depressions and another of which is in contact with said second plurality of depressions to support the electron gun structure centrally of said tubular portion.

FREDERICK HERMES NICOLL.
